UNITED STATES PATENT OFFICE.

ROBERT D. WEBB, OF MINDEN, LOUISIANA.

AUTOMATIC WEIGHING AND DUMPING MACHINE.

No. 820,455.

Specification of Letters Patent.

Patented May 15, 1906.

Application filed April 8, 1905. Serial No. 254,547.

To all whom it may concern:

Be it known that I, ROBERT D. WEBB, a citizen of the United States, residing at Minden, in the parish of Webster and State of Louisiana, have invented certain new and useful Improvements in Automatic Weighing and Dumping Machines, of which the following is a specification.

My invention relates to automatic weighing and dumping machines, which may be differently constructed, but preferably has many of the features of my application for Letters Patent, Serial No. 245,571; and my invention consists in the arrangement of toggles in connection with scale-beams, each swinging from the same axis, and in providing the receptacles with movable bottoms or valves and means for locking and opening the same, as fully set forth hereinafter, and as illustrated in the accompanying drawings, in which—

Figure 1 is an elevation in part section of a weighing and dumping machine embodying my improvements. Fig. 2 is a sectional plan.

Within the mouth of the chute or hopper A, communicating with the source of supply, is centrally pivoted a valve D, having two faces diverging from the center downward, so that when the valve is in one position the chute will be opened above a receptacle supported by one of two scales B B' and when in the other position will be opened above a receptacle supported by the other scale. These scales may be pivoted in any suitable manner—as, for instance, in my application, Serial No. 245,571—but preferably they are suspended from a central pivot or shaft a, supported by a main frame C. Each scale consists of a beam l and may be provided with the usual suitable adjustable weights and counterweights, as desired. Suspended to the scale-beams below the mouth of the chute at each side are receptacles m and m', which may be suitably connected. Thus each of the beams l is connected to operate the valve D, a link o being connected to the joint of a toggle r r and to the scale-beam l below and one member of the toggle being connected to an arm g on the shaft f of the valve, as illustrated, so that as either receptacle sinks—as, for instance, the receptacle m—the connected toggles will be broken and the valve D will be swung to one side to close the chute above the descending receptacle, while the rising of the other receptacle will

straighten the toggle connected therewith and interpose its members in a straight line between their pivot and the arm g, so as to hold the valve D in its new position during the filling of the elevated receptacle. When the latter is filled, its weight will cause its descent, breaking the toggle to which the receptacle is connected, again shifting the valve, which will be secured in its new position as the opposite receptacle reaches the limit of its upward movement. It will be seen that owing to the connections shown as one receptacle descends its weight will be exerted to lift the other receptacle.

With the above-described parts are combined means whereby the material in each receptacle, as soon as the latter has been properly filled, will be discharged, and the discharge from both receptacles is received by a chute E, or in any suitable way, from which it may pass to a bag held beneath or to any convenient receiver. As shown, each receptacle m m' is of metal or other suitable rigid material and is provided with a bottom v, hinged to one side at w, counterweighted, if necessary, and provided with an arm or extension u, between which and a pin t on the receptacle is interposed a toggle s, and a link q extends from the joint of this toggle to a pin p, projecting from the beam l at a point distant from the point y, where the receptacle is suspended by the beam l, so that as the beam l swings downward the pin p will be carried down with the link q, moving more rapidly than the receptacle, thus breaking the toggle s and swinging the bottom v to an open position, whereby the material in the receptacle is discharged. When the receptacle is again carried upward and the scale-beam takes a horizontal position, the link q will carry upward the pivot of the toggles, bringing the two sections thereof into line, and thereby locking the hinged bottom of the receptacles, so that as one fills the other discharges.

It will be evident that other forms of movable bottoms or valves for the receptacles may be employed, as well as other means for causing the same to be opened when the scale is tilted or otherwise moved on the receptacle receiving its charge.

Without limiting myself to the precise con-

struction and arrangement of parts shown, I claim as my invention—

1. The combination in an automatic weighing-machine, of a chute, a valve at the mouth of the chute, two scale-beams having a common pivot below said valve and supporting receptacles, two toggles, each connected to operate the valve, and a link between each toggle and the scale-beam supporting the receptacle below said toggle, substantially as set forth.
2. The combination in a weighing-machine, of a chute, a valve at the mouth of the chute, two scale-beams pivoted at their inner ends and extending outward in opposite directions, toggles connected with the frame and with the valve, and links connecting the joint of each toggle with the adjacent scale-beam, substantially as set forth.
3. The combination with a chute and with a valve hinged in the mouth of the chute to open and close opposite sides thereof alternately, of two scale-beams, each having a long and short arm, the short arm of each beam supporting a receptacle, a toggle, and a link connecting the same with each short arm, said toggle connected to the frame and to the valve, substantially as set forth.
4. The combination with the valve and scale-beams of an automatic weighing and dumping machine, of a receptacle supported by each scale-beam, and provided with a movable bottom or valve, a toggle connecting the valve to the receptacle, and connections between the toggle and scale-beam whereby to open said valve as the receptacle begins to descend when filled, substantially as set forth.
5. The combination with the chute, valve and scale-beams and receptacles of a weighing-machine, of connections between the beams and valve for shifting the latter to open and close the mouth of the chute at opposite sides alternately, a bottom hinged to each receptacle and provided with an arm and with a toggle extending between said arm and a point on the receptacle, and connections between the toggles and the beams whereby the sections of each toggle are brought into line as the receptacle rises and are carried out of line as the receptacle descends, substantially as set forth.
6. The combination of the chute, valve, scale-beams, toggles connected by links to the beams, receptacles provided with pivoted bottoms, toggles and connections between the toggles and the scale-beams, substantially as set forth.
7. In an automatic weighing and dumping machine, the combination with scale-beams,
- of a receptacle supported by each scale-beam and provided with a movable bottom or valve, and toggles connecting the receptacle and valve, and connections between the toggles and scale-beams whereby the valve is opened on the descent and closed on the ascent of each receptacle, substantially as set forth.
8. In an automatic weighing and dumping machine, the combination of the scale-beams, receptacles, a bottom hinged to each receptacle and provided with an arm and with a toggle extending between said arm and a point on the receptacle, and connections between the toggles and beams whereby the sections of each toggle are brought into line as the corresponding receptacle rises and are carried out of line as the corresponding receptacle descends, substantially as set forth.
9. In an automatic weighing and dumping machine, the combination with the main inlet-valve and scale-beams, of a receptacle, supported by each scale-beam, provided with a movable bottom or valve, toggles connecting the valve to the receptacle, and connections between the scale-beams and the toggles whereby the bottom of each receptacle is opened when the inlet-valve is closed and vice versa alternately, substantially as set forth.
10. In an automatic weighing and dumping machine, the combination of the scale-beams, receptacles supported by said scale-beams and provided with movable bottoms or valves having toggle connection with the receptacles, and connections between the toggles and the beams whereby the members of each toggle are brought into line as the corresponding receptacle rises, thereby closing the valve and locking it in closed position, substantially as set forth.
11. In an automatic weighing and dumping machine, the combination of the scale-beams, receptacles supported by said scale-beams and provided with movable bottoms or valves having toggle connections with the receptacles, and connections between the toggles and the beams whereby the members of each toggle are carried out of line as the corresponding receptacle descends thereby opening the valve and holding it in opened position, substantially as set forth.

In testimony whereof I have signed my name to this specification in the presence of two subscribing witnesses.
